J. EDELMAN

FOUNTAIN PEN

Filed Aug. 20, 1923

UNITED STATES PATENT OFFICE.

JACOB EDELMAN, OF BROOKLYN, NEW YORK, ASSIGNOR TO ROSE EDELMAN.

FOUNTAIN PEN.

Application filed August 20, 1923. Serial No. 658,336.

To all whom it may concern:

Be it known that I, JACOB EDELMAN, a citizen of Ukrania, and resident of Brooklyn, in the county of Kings and State of New York, have invented certain new and useful Improvements in Fountain Pens, of which the following is a specification.

My present invention relates to fountain pens and is more particularly concerned 10 with pens of the self-filling type.

It is among the objects of the invention to provide a fountain pen of conventional external appearance, the filling appurtenances of which occupy a minimum of the 15 volume within the pen so that a maximum space is afforded for ink.

It is another object to provide a pen of the above type in which the filling operation can be expeditiously performed without 20 likelihood of parts jamming or the hands becoming soiled and all of the parts of which shall be of relatively permanent character, not subject to deterioration by contact with the ink or with the air.

25 Another object of the invention is to provide a pen of the above type which can be expeditiously and economically manufactured.

Other objects will be in part obvious and 30 in part pointed out hereinafter.

In the accompanying drawings in which are shown one or more of the various possible embodiments of the several features of this invention,

35 Fig. 1 is a view in longitudinal cross-section of the pen immediately preparatory to drawing in a charge of ink.

Fig. 2 is a fragmentary sectional view on a greatly enlarged scale of the upper end 40 of the pen showing the parts telescoped,

Figs. 3 and 4 are transverse sectional views taken respectively along the lines 3—3 and 4—4 of Fig. 2,

Fig. 5 is a fragmentary sectional view 45 showing a modified form of connection between the operating cap and the stem.

Fig. 6 is a sectional view taken along the line 6—6 of Fig. 5,

Fig. 7 is a fragmentary view generally 50 similar to Fig. 6 of a further modified form showing the stem extended, and

Fig. 8 is a fragmentary sectional view showing the relation of the cap to the barrel in the embodiment of Fig. 7.

55 Referring now to the drawings, I have

shown a fountain pen including a barrel 10 having threaded thereinto the feed piece 11 with the usual feed 12 and pen point 13. A plunger 14, preferably of a special construction to be described below, serves for filling 60 and is operated through a stem having preferably sections 15, 16, 17 and 18 telescoped, as best shown in Fig. 2 when the pen is in use, the outer section 18 of said stem being connected to a cap constituting a finger piece 65 19 threaded as at 20 into the outer end of and flush with said barrel and extending over the telescoped stem sections so that the plunger 14 is normally near the top of the barrel and substantially the entire volume 70 of the barrel is available for containing ink.

In the preferred embodiment, the lowermost section of the telescoping stem is a rod 15 which may be of brass threaded into a 75 vulcanite stud member 21 having a head 22 pressed by means of a nut 23 about the stud against the outer surface preferably of a cork plunger washer 24. The rod 15 has a transverse pin 25 preferably square 80 in cross-section fitting into a slot 26 in the tubular stem section 16. The slot 26 has an offset 27 extending toward the left to form a bayonet connection, said offset preferably at right angles to the length of the slot. 85 At the upper end the tube section 26 has a pair of diametrically opposite preferably square protruding lugs 28 which may be either riveted thereto or embossed or pressed out from the material thereof and which 90 extend with little lateral clearance into a pair of bayonet slots 29 similar to slots 26 and in tube section 17 the latter of diameter sufficiently large to telescope over section 16. In a similar way, the third section 18 95 is provided with diametrically opposite bayonet slots 30 coacting with square lugs 31 rigid with the outer end of the tube 17. In the embodiment of Fig. 1, the operating cap 19 is connected to the stem section 18 100 by a pair of pins 32 secured in the lower end of said cap and projecting inward therefrom into bayonet slots 33 in an enlargement 33¹ at the upper end of section 18¹, the offset of said slot extending in the direction opposite to the offsets 27 in the 105 slots of the various stem sections, that is toward the right. The barrel is preferably provided with an integral inner ledge 34 immediately below the screw threaded end 110

20 said ledge serving as a stop for the plunger 14 in the withdrawing or pumping action of the plunger.

In operation, to fill the pen, the cap 19 is 5 unthreaded and withdrawn to its limit, while the unthreading movement is continued. In this withdrawal action, it will be seen that the various square pins 25, 28, 10 31 and 32 will be moved longitudinally of the associated slots to draw the telescoped sections apart and in the continued rotary action, the pins will move into the lateral offsets as best shown in Fig. 1, the pins 32 on the cap similarly moving into lateral 15 slot offsets 33. The cap is now pushed inward, the pins thereon delivering the thrust through the bayonet slots in the outer tube section 18 which latter transmits the thrust through the square pins 31 in the second 20 section, etc., the extended sections forming a relatively rigid stem to force the plunger 14 down to the bottom of the barrel. The parts as shown are proportioned so that when the cap reaches contact with the barrel, the plunger will have substantially 25 reached the feed piece, the head 22 of the stud in that relation protruding into close contiguity to the feed piece 12. The pen being now dipped into the well of ink, a single withdrawal action of the cap piece 30 will suffice to fill the barrel completely with ink, the plunger being limited in this action by contact against the integral stop ledge 34. The pen being now filled, the cap is 35 returned to its home position by rotating it toward the right while pushing inward thereon. In this operation, it will be seen that the various pins will move out of the offsets of the bayonet slots and will then move lengthwise of said slots for collapse of 40 the stem. After the cap is brought into contact with the barrel, it is threaded thereonto as best shown in Fig. 2, said final threading operation advancing the cap a distance only 45 in the order of about $\frac{1}{16}$ ", so that the plunger 14 is advanced inward through a minute range, aiding in feeding the ink toward the pen point whereby writing can be easily started without shaking the pen.

50 It will be seen that according to the present invention, the collapsed plunger stem is accommodated in the cap piece 19 beyond the barrel, so that the entire length and cross-section of the barrel may be filled with 55 ink by operation of cap 19 as distinguished from pens in which the plunger stem or air tubes occupy an appreciable or substantial proportion of the volume within the barrel.

60 My pen, however, is substantially conventional in external appearance without protruding screws operating levers or handles.

65 The bayonet slots having offsets at right angles to the length of the tubes, it will be seen that with a minimum length of section, a maximum length of plunger stem is pro-

vided, so that the length of the collapsed stem is accommodated in a cap piece of comparatively short length, as distinguished from constructions in which the bayonet slots are provided with reversely bent ends. 70

The plunger construction shown, effectively maintains the ink out of contact with the stem which by reason of its collapsing construction can be readily produced only of metal, and at the present state of technical development, metal parts capable of resisting the erosive effect of ink would add excessively to the cost of the pen. 75

In Fig. 5 is shown an alternative embodiment generally similar to Figs. 1 and 2 except that in lieu of the bayonet slot connection between the operating cap 19¹ and the first section 18¹, I provide a reversed construction in which lugs 35 are pressed outward from the upper end of stem section 18¹ and fit into a slot 36 with a rectangular offset 37 at its lower end forming a bayonet slot preferably in a metallic inset sleeve 38 press-fitted within the cap piece 19. 80

In Fig. 7 is shown a further alternative embodiment in which I provide in the upper tubular stem section 18² two pairs of longitudinal slots, one pair 39 of diametrically opposite slots having offsets 40 at their lower ends extending toward the left for accommodating pins 41 in the succeeding stem section 17², and the other pair of slots 42 midway between said first pair, having offsets 43 at their upper ends extending toward the right to accommodate lugs 44 protruding inward from cap 19². By this construction it will be seen that stem section 18² may be of larger diameter than in the other embodiments, and may in fact fit closely within cap 19². It would therefore be practicable to employ a stem of five rather than four sections in this case, so that the cap 19² could be made correspondingly shorter. In Fig. 7 I have also indicated in lieu of the threaded connection between the cap 19² and the barrel 10² a bayonet slot connection 45, the bayonet slot in the barrel being preferably undercut so that the pins therefor protruding from the cap 19² will not be visible when the pen is in assembled or closed position, as shown in Fig. 8. As shown, the pins coacting with bayonet slots 45 may be integral projections of lugs 44. 95

100 It will thus be seen that there is herein described apparatus in which the several features of this invention are embodied, and which apparatus in its action attains the various objects of the invention and is well suited to meet the requirements of practical use. 110

115 As many changes could be made in the above construction and many apparently widely different embodiments of this invention could be made without departing from the scope thereof, it is intended that all mat- 120

ter contained in the above description or shown in the accompanying drawing shall be interpreted as illustrative and not in a limiting sense.

5 Having thus described my invention, what I claim as new and desire to secure by Letters Patent of the United States is:

1. In a fountain pen, in combination, a barrel, a plunger stem operating and housing cap releasably threaded to the outer end of the barrel and continuous therewith, a filling plunger, an operating stem for said plunger having a plurality of telescoping sections with bayonet slot connections therebetween and a bayonet slot connection between said cap and the outer of the stem sections, said stem sections normally telescoped with respect to each other and into said cap with the plunger retained in outermost position in the barrel, said parts being constructed and arranged in such manner that in the unthreading and withdrawal movement of the cap, the plunger stem becomes extended and the bayonet slot connections rendered effective for plunger operation, and in the replacement of the cap, the telescoping connections become released and the stem collapsed within the cap.

2. In a fountain pen, in combination, a barrel, a plunger therein, an operating stem for said plunger comprising a plurality of telescoping sections, each having a bayonet slot connection with respect to the consecutive one, an operating and housing cap for said plunger, releasably threaded to the end of said barrel, said cap having bayonet pins at the end thereof nearest the barrel projecting into a bayonet slot in the outer stem section, the offset end of which slot extends in a direction opposite that of the offsets of the bayonet slot connections between the telescoping stem sections whereby in unthreading the cap and drawing it outward, the cap and stem enter into extended position and in the continued rotary displacement of the cap in the unthreading direction, the various bayonet locks are automatically established

to form a relatively rigid stem for operating the plunger and whereby in the rotation of the cap toward locking position, the bayonet locks are released and in the return of the cap toward the cap, the stem becomes automatically collapsed into the barrel.

3. In a fountain pen, in combination, a barrel, a filling plunger therein, a telescoping operating stem for said plunger, an operating member connected to the outer section of said stem, said operating member comprising a cap releasably threaded upon said barrel, bayonet slot connections between successive stem sections, and a bayonet slot connection between the outer stem section and said cap, said connection comprising pins rigid with said outer section and a sleeve rigidly telescoped into said cap and having bayonet slots into which said pins extend.

4. In a fountain pen, in combination, a barrel, a plunger therein, an operating stem therefor comprising a rod connected to the plunger and a plurality of tubular telescoping sections, said rod having transverse lugs fitting in a pair of corresponding bayonet slots lengthwise of the contiguous section and similar bayonet slot connections between each tubular section and the succeeding one, and pins projecting inward from the cap into the second pair of bayonet slots in the outer or extreme section of the telescoping stem.

5. In a fountain pen, in combination, a plunger comprising a washer of cork, a solid stud on the stem side of the washer of vulcanite through said plunger and having a head of diameter smaller than that of said plunger, a metallic operating stem for said plunger threaded into said stud and a nut threaded about said stud to clamp the head of the stud against said washer.

Signed at New York, in the county of New York and State of New York, this 11th day of August, 1923.

JACOB EDELMAN.
